UNITED STATES PATENT OFFICE.

PAUL A. HASSELBLATT, OF ROCKVILLE, MARYLAND.

MUSIC-SHEET HOLDER AND TURNER.

1,409,171.

Specification of Letters Patent. Patented Mar. 14, 1922.

Application filed December 3, 1920. Serial No. 428,045.

To all whom it may concern:

Be it known that I, PAUL A. HASSELBLATT, a citizen of Russia, residing at Rockville, in the county of Montgomery and State of Maryland, have invented certain new and useful Improvements in Music-Sheet Holders and Turners, of which the following is a specification.

This invention relates to a device for holding and properly presenting to the view of the musician the successive pages of music contained on a continuous sheet or strip of paper. The music for one composition is printed on one side of the sheet in the form of successive spaced pages and the sheet is preferably folded transversely on lines between pages, thus making a neat rectangular package as a whole. It will of course be obvious that a second composition may be printed on the back of the sheet and that the sheet may be wide enough to contain two compositions or sets of musical notations side by side. One main purpose of the invention is to enable the musician to remove from view one page of the music when it is finished and bring into view the next page easily and quickly without pausing in his playing, and in the preferred form without removing his hands from the instrument which he is playing. It includes means by which a single movement applying power such as pressing the foot on a spring support pedal in convenient position will operate automatically to carry from view the page of finished music and bring into view in proper position the next page, and which will at the same time neatly lay each finished page in succession in folded condition on those preceding it out of view. In other words, the pages are drawn from a neatly folded package, are successively presented to the view of the operator, and are then removed from view and folded by the successive automatic operations of my device. The operation of drawing this sheet is automatic in that it makes a single pressure of the foot move the sheet longitudinally exactly the right amount to expose the next page. The device, furthermore, is in the nature of an attachment which may be placed on a stand of its own or on a musical instrument such as a piano, and may be so designed as to add to instead of detracting from the appearance of the instrument. A flexible drive shaft or connection from the foot pedal or manual operating means to the

sheet holding and moving mechanism makes it possible to place the foot pedal in any convenient or preferred position with regard to the music holding mechanism. The holder for the page of music on view is, furthermore, adjustable in reference to the vertical plane so as to bring it into proper angular position so as to be best seen by the musician in accordance with the difference in position or height of the operator. Other novel features will be apparent from the following description taken with the drawings and claims.

In the drawings:

Figure 1 is a front view of my device mounted on a stand especially adapted to receive it.

Figure 2 is a side view of what is shown in Figure 1, parts of the music holding and moving means being in section.

Figure 3 is a side view of the foot operating pedal from the side opposite to that shown in Figure 2.

Figure 4 is a detached perspective view of parts of the foot pedal.

Figure 5 is an enlarged sectional view of the one-way drive connection between the flexible drive shaft and the friction roller of the music support.

Figure 6 is a plan view looking down on the drive parts to which the flexible shaft is connected as illustrated in Figure 5.

Figure 7 is a front view of a piano having my invention in operative position thereon showing the parts more or less diagrammatically.

Figure 8 is a side view partly in section of what is shown in Figure 7.

Figure 9 is a transverse section of music supporting plate 57 shown in Figure 8 partly broken away.

In Figures 1 and 2 of the drawings I have shown my music holder mounted on a stand 10 especially made for the purpose and which may be easily moved about to any position where desired, and may be of any form or height desired. On this stand 10 there is mounted a plate or platform 11 to which is hinged at 12 the music holder embodying the bottom plate 13 and the upwardly extending plate 14 which preferably joins the plate 13 at the bottom at an angle of about forty-five degrees. The music sheet 15 in folded condition rests at its lower edge on the ledge 16 on the front face of the plate 14 and naturally retains

its position by gravity. A light frame having side vertical bars 17 is pivoted at the top 20 to side ears 22' of the music holder and there may be a cross rod or roller at 5 this point over which the music sheet passes. The frame 17 has a rod 18 at the bottom under which the music sheet is drawn and from which it passes up to the roller at 10 20 exposing to view a sheet of music since the rollers 18 and 20 are spaced apart slightly more than the length of a page of music. A roller 21 is mounted on the upwardly extending side parts 22' rigid with the plates 13 and 14, and the music 15 sheet passes under or behind this roller 21 so as to hold it smooth and under some tension extending from roller 18 to 20. After leaving roller 21 the sheet passes between rollers 22 and 23, which rollers are 20 mounted in the projections 22' and are frictionally pressed together by springs 24 bearing on the shaft of the upper roller 23 and tending to move it downward in its slot bearings to grip and frictionally 25 engage the music sheet. This frictional engagement may be increased by placing on the roller 22 friction rings 25. The music sheet passing between rollers 22 and 23 will of course from its resiliency extend some- 30 what to the rear but through gravity will tend to move downward to the plate 13, and when the end of a page where the fold is strikes the plate 13 it will come in contact with the end ledge 26 which will prevent 35 it from passing over the edge of the plate, and it will then fold down flat on the plate 13 and will be held in proper position by the lower projections or ledge 27. The suc- 40 cessive pages will of course fold in opposite directions automatically as they come into the space between the parts 13 and 14. It will be noted that the music holding and carrying device embodying the plates 13 and 14 is adjustably supported on its pivot 45 12 by a pivoted rod 28 secured to the under side of plate 13 and at its other end en- gaging the teeth or notches 29 carried by the plate 11, and this permits turning the music holding device so that the sheet ex- 50 posed to view will occupy different angles.

The friction roller 22 has at one end se- 55 cured to its bearing shaft a bevel gear 30 which meshes with a bevel gear 31 mounted to turn in the projecting support 32 se- cured to one side of the music holding de- 60 vice. The bevel gear 31 has a one-way drive connection to a flexible drive shaft 33 of well known construction and this drive shaft is turned by the operation of a foot 65 pedal 34 pivoted at 35 and normally held in its upper position by the spring 36. The foot pedal has at its free end an arm 37 slotted on a horizontal plane and fitting and held in position on the end of projection 38 carried by the vertical toothed bar 39 which

moves vertically with guideways in the fixed support 40 connected to the foot pedal sup- port 41. A pressure of the foot on the foot pedal will move the rack bar down and on release of the foot pressure the spring 36 70 will return it to its upper position, there of course being stops to limit its motion in both directions. A gear wheel 42 having gear teeth in mesh with the teeth of the rack bar 39 is mounted to turn in the support 43 on 75 the foot pedal support 41 and is so con- nected to the flexible drive shaft 33 as to turn it in either direction. The parts of the drive mechanism and the length of the movement of the rack bar 39 are so propor- 80 tioned and regulated that a down stroke on the foot pedal will turn the friction roller 22 exactly enough to draw the music sheet upward a distance equal to the length of a single page of music and thus the operator 85 with his foot pushes down the pedal until the stop is reached and this automatically removes one music page from view and brings into view the next page. However, in order that the upward movement of the foot pedal 90 under the influence of the spring 36 and the consequent reverse turning of the flexible shaft shall not result in the reverse move- 95 ment of the friction roller 22 and conse- quently the music sheet, I provide a one- way drive connection between the upper end of the drive shaft 33 and the bevel gear 31. This is illustrated in Figures 5 and 6, where it will be seen that the bevel gear 31 has a downwardly projecting cylindrical portion 100 44 turning in a bearing socket in the bracket 32 and that in its upper face there is an en- larged cylindrical depression 45. Within and at the outer margin of this cylindrical depression 45 there is a ring 46 having on 105 its inner surface ratchet teeth 47 facing in one direction, and this ring 46 is prevented from turning in the bevel gear member by a locking pin 48. Mounted centrally with- in the socket 44 of the gear wheel 31 is a 110 member 49 having a lower cylindrical por- tion rotative in the bevel gear member and with an enlarged head 50, the projecting por- 115 tion of that head serving to support this member in the bevel gear body. Pawls 51 are pivoted to the head 50 and have points 120 engaging the teeth 47 of the ring 46 to pre- vent relative turning of the head 50 and the ring 46 and gear 31 in one direction, and there is a spring 52 extending through the 125 head and tending to force these pawls out- wardly into engagement. The bevel gear 31 has at its lower outer margin teeth 53 facing in one direction and there is a pawl 54 pivoted at 55 engaging these teeth to pre- 130 vent the gear wheel 31 from accidentally turning in the reverse direction and this pawl is pressed into position by a spring 56.

In the form of the invention shown in Figures 7 and 8, applied to a piano, the main 135

elements of structure and the method of operation are the same as that described in connection with Figures 1 and 2 and thus the showing of those common features is 5 more or less diagrammatic. In using the device on a piano, however, it is preferable to have the music holding part of the device in front of the piano immediately above the key board and to have the finished sheets carried up and deposited in a holder placed on 10 top of the piano. Instead, therefore, of having the plates for carrying the music before and after exhibition made in one piece or secured together, they are made separately 15 and the plate 57, corresponding in a sense to plate 14, is allowed to rest at an angle on top of the ledge 58 of the piano and of course carries with it the frame and rollers for holding the exposed sheet like those used 20 in Figures 1 and 2. In this instance the sheet after leaving roller 21 and passing between the frictional rollers 22 and 23, is deposited and folded on an inclined plate 59 corresponding in a sense with the bottom 25 plate 13 of Figures 1 and 2, but which is mounted on top of the piano. This plate has of course the transverse upwardly projecting end flanges to receive the music sheet. The flexible drive shaft may of 30 course be mounted in any suitable way, such for instance as to pass under and behind the piano as shown. It will be observed that the device may be used on a piano without any changes in the piano itself, and that it 35 may be held in proper position by any suitable means on the piano.

In Figure 7 I have shown the music holding device as wide enough to receive a music sheet carrying two sets of musical notations 40 side by side such as may be necessary in playing duets, but have shown in place a narrow music sheet adapted to contain a single set of notations. In order that this wider arrangement may properly receive and 45 guide the narrow sheet when desired, the plate 57 is formed with a central vertical depression or groove shown in Figure 9 with side margins or edges 60 sufficiently far apart to receive and hold in place the music sheet 50 fitting in it. A cross bar 61 may be secured in the frame 17 above the roller 18 and provided with pivoted lugs 62 to fit against the edges of the narrow music sheet to properly guide it. In this instance also the roller 55 23 may be provided on its surface with marks to indicate the proper position on it for the narrow sheet.

It will of course be understood that my invention is not limited to the particular uses 60 specifically shown and described, and that it is of course adapted for use in various ways. Furthermore, while I prefer to use a folded sheet of music, it will be understood that the invention in its broader aspects is 65 not limited to that particular form. The

particular means for driving and operating the mechanism have been shown simply to illustrate the broad ideas and method of operation which are structurally claimed by me as my invention.

70

Having thus described the invention, what is claimed as new and desired to be secured by Letters Patent is:

1. In a device for holding and presenting to view successively the pages of continuous sheet music on an elongated substantially uniform flexible strip comprising in combination means for holding the continuous music sheet including a stationary frame on which one page is exhibited, mechanism 75 adapted to operate on a single application of power to move that page out of position for exhibition and to bring the succeeding page into such position.

2. In a device for holding and presenting to view successively the pages of continuous sheet music on an elongated substantially uniform flexible strip comprising in combination means for holding the continuous music sheet including a stationary frame on 80 which one page is exhibited, foot operated mechanism adapted to operate to move that page out of position for exhibition and to bring the succeeding page into such position.

3. In a device for holding and presenting to view successively the pages of continuous sheet music comprising in combination means for holding a continuous folded music sheet, rollers over which said sheet may be passed so spaced and positioned as to 95 exhibit one page at a time, mechanism for so operating said rollers as to frictionally draw said sheet removing one page from view and bringing the successive page into view, the operating means including automatic means for so regulating the extent of the movement on the application of power as to correspond to the length of the page.

4. In a device for holding and presenting to view successively the pages of continuous sheet music comprising in combination means for holding a folded music sheet with one 110 page only exhibited to view on a stationary supporting part, mechanism for simultaneously drawing said page across the surface 115 of the supporting part and out of position and bringing the succeeding page into position for view, and means for folding the pages which have successively passed from view.

120

5. In a device for holding and presenting to view successively the pages of continuous sheet music comprising in combination means for holding the continuous music sheet with one page exhibited on a stationary supporting part, mechanism for drawing that page across the surface of the supporting part out of position and bringing the next page into position, one way acting foot operated motor mechanism adapted to 125 130

rest on the floor and an elongated flexible rotary driving connection between said foot operated motor mechanism and sheet drawing mechanism.

- 5 6. In a device for holding and presenting to view successively the pages of continuous sheet music comprising in combination means for holding a folded music sheet, a roller in front of and at approximately the lowest 10 point of said holding means under which the sheets may pass, a pair of rollers above but in a vertical plane to the rear of said lower roller adapted to receive between them and frictionally grip said sheet extending 15 up from the lower roller and spaced from said lower roller a distance slightly greater than the length of a page of music on said sheet, flexible one-way acting means for driving one of said pairs of rollers to draw 20 the sheet, and means connected to and movable with the free end of said flexible means for operating said flexible means and connected roller to move said continuous sheet the length of a page of music.
- 25 7. In a device for holding and presenting to view successively the pages of continuous sheet music comprising in combination means for holding a folded music sheet, a roller in front of and at approximately the lowest 30 point of said holding means under which the sheets may pass, a pair of rollers above but in a vertical plane to the rear of said lower roller adapted to receive between them and frictionally grip said sheet extending 35 up from the lower roller and spaced from said lower roller a distance slightly greater than the length of a page of music on said sheet, flexible one-way acting means for driving one of said pairs of rollers to draw 40 the sheet, and means connected to and movable with the free end of said flexible means for operating said flexible means and connected roller to move said continuous sheet the length of a page of music, a receptacle 45 in position to receive the sheet as it leaves said pair of rollers and so constructed as to automatically fold it.
8. In a device for holding and presenting to view successively the pages of continuous 50 sheet music comprising in combination a movable member adapted to be carried by any suitable support embodying means for holding the folded sheet music with one page exposed to view at an angle to the vertical, 55 rollers for drawing said sheet longitudinally bringing the pages of the sheet successively but intermittently into position for view and a receptacle for receiving the successive sheets after passing the point of view including means for automatically folding the sheets, flexible means connected at one end 60 to said drawing rollers to drive the same in one direction to move said sheet and manually operable means connected to the other 65 end of said flexible means for operating it.

9. In a device for holding and presenting to view successively the pages of continuous sheet music comprising in combination a movable member adapted to be carried by any suitable support embodying means for holding the folded sheet music with one page exposed to view at an angle to the vertical, rollers for drawing said sheet longitudinally bringing the pages of the sheet successively but intermittently into position 70 for view and a receptacle for receiving the successive sheets after passing the point of view including means for automatically folding the sheets, flexible means connected at one end to said drawing rollers to drive 75 the same in one direction to move said sheet and manually operable means connected to the other end of said flexible means for operating it and means for adjusting the angle to the vertical of said sheet carrying means as desired to properly present the visible pages to view.

10. In a device for holding and presenting to view in succession the pages of music printed in succession at regularly spaced 90 intervals on a thin elongated sheet of material having substantially uniform flexibility throughout, comprising a fixed support rectangular in outline of such size as to be adapted to receive across its exposed 95 face a section of said sheet containing a full page of music, mechanism for drawing said sheet longitudinally across the face of said support and for holding the section on said support flat and smooth both when moving 100 and when stationary, and mechanism for so operating said drawing mechanism as to cause it to move said sheet longitudinally a sufficient distance on each application of power to bring the next succeeding page of 105 music on the sheet to proper position on said support.

11. In a device for holding and presenting to view in succession the pages of music printed in succession at regularly spaced 110 intervals on a thin elongated sheet of material having substantially uniform flexibility throughout, comprising a fixed support rectangular in outline of such size as to be adapted to receive across its exposed 115 face a section of said sheet containing a full page of music, foot operated mechanism for drawing said sheet longitudinally across the face of said support and for holding the section on said support flat and smooth both 120 when moving and when stationary, and mechanism for so operating said drawing mechanism as to cause it to move said sheet longitudinally a sufficient distance on each application of power to bring the next succeeding page of music on the sheet to proper 125 position on said support.

12. In a device for holding and presenting to view in succession the pages of music printed in succession at regularly spaced 130

- intervals on a thin elongated sheet of material having substantially uniform flexibility throughout, comprising a fixed support rectangular in outline of such size as to be adapted receive across its exposed face a section of said sheet containing a full page of music, stationary means at the rear of said support for holding said sheet in folded condition with the folds at the lines between 10 pages and alternately reversed in such position that the end portion of the sheet may pass across the lower edge of said support and then at an angle upward over and beyond the face of said support, mechanism beyond the upper end of said support for engaging and drawing said sheet across said support and mechanism for so operating said drawing mechanism as to cause it to move said sheet longitudinally a sufficient 20 distance on each application of power to bring the next succeeding page of music on the sheet to proper position on said support.
13. In a device for holding and presenting to view in succession the pages of music printed in succession at regularly spaced intervals on a thin elongated sheet of material having substantially uniform flexibility throughout, comprising a fixed support rectangular in outline of such size as to be adapted to receive across its exposed face a section of said sheet containing a full page of music, stationary means at the rear of said support for holding said sheet in folded condition with the folds at the lines between 30 pages and alternately reversed in such position that the end portion of the sheet may pass across the lower edge of said support and then at an angle upward over and beyond the face of said support, mechanism beyond the upper end of said support for engaging and drawing said sheet across said support and means at the rear of said drawing means for receiving and automatically folding said sheet.
14. In a device of the class described adapted to be mounted on a support, the combination with means for holding in folded condition an elongated strip of flexible material having thereon in succession 40 longitudinal pages of music, a movable frame in front of said holding means, means normally resting in fixed position at a slight angle to the vertical having a horizontal guide surface at its lower edge under which said strip may be drawn and bent upward with a complete page of music lying flat along the exposed face of said frame, means above said frame for engaging said strip, drawing it longitudinally and depositing the portion 50 of said strip which has passed it in the rear of drawing means, foot operated motor mechanism adapted to rest on the floor, and flexible drive connection from said motor mechanism to said sheet drawing mechanism, the structure of such foot operated mechanism and of its connection to the drawing mechanism being such that a single pressing operation by the foot will so move said strip as to carry one page of 60 music out of view and bring the succeeding page into view on said frame.
15. In a device of the class described adapted to be mounted on a support, the combination with a plate like holder at a slight incline to the vertical having a horizontal ledge at the bottom adapted to support an elongated strip of flexible material having thereon in succession longitudinally 70 pages of music, the said strip being folded on transverse lines between pages, of a frame in front of said holder substantially parallel therewith resting at its lower end by gravity against said ledge on the holder and hinged at its upper edge, the bottom 80 edge being in a horizontal line adapted to have the strip drawn between it and said ledge and then bent and pulled up over the exposed face of the frame, means beyond said upper hinged end of the frame for engaging and drawing said strip longitudinally 90 across said frame and depositing it in the rear thereof, the said drawing means being so constructed that each application of power will cause it to move the sheet a predetermined fixed distance.

In testimony whereof I affix my signature.

PAUL A. HASSELBLATT.
